[57] CLAIM

The ornamental design for a luggage lock, as shown and described.

DESCRIPTION

FIG. 1 is a perspective view of a luggage lock showing my new design, with the hasp portion shown separated from the lock body;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a bottom plan view thereof; and

FIG. 8 is a front elevational view of an alternate embodiment thereof, the only difference residing in the location of the hasp at the bottom.

FIG.6

FIG.1
